UNITED STATES PATENT OFFICE.

FRANK I. GUNNELL AND RALPH MILLER, OF LOS ANGELES, CALIFORNIA; SAID MILLER ASSIGNOR TO CHARLES O. GUNNELL AND KATHERINE GUNNELL, OF LOS ANGELES, CALIFORNIA.

AUTOMATIC MIXER FOR SODA-DISPENSING FAUCETS.

Application filed October 5, 1926. Serial No. 139,605.

Our invention relates generally to soda dispensing faucets and more particularly to a device that is applied to the faucet and which will act automatically to effect a 5 thorough mixing of the charged water that discharges from the faucet and the syrup or flavoring extract that is contained in a drinking glass, or the like, that is positioned beneath the faucet.

10 The principal objects of our invention are to provide an automatic mixing device of the character referred to that is relatively simple in construction, capable of being readily applied to practically all charged 15 water dispensing faucets, to provide a mixing device that will be effective in saving much of the time and labor that is ordinarily involved in the mixing of the charged water with syrups, fruit juices, and the like, 20 that are contained in the drinking glass, and further, to provide a mixing attachment for soda dispensing faucets that is automatically thrown into operation as the syrup containing glass is placed in position beneath the 25 spout or nozzle through which the charged water discharges.

With the foregoing and other objects in view, our invention consists in certain novel features of construction and arrangement of 30 parts that will hereinafter be more fully described and claimed and illustrated in the accompanying drawing, in which:—

Fig. 1 is a vertical section taken through the center of a mixing device of our improved construction and showing the same applied to a faucet.

Fig. 2 is a side elevational view of the mixing device with parts thereof broken away and in section.

40 Fig. 3 is a horizontal section taken on the line 3—3 of Fig. 1.

Referring by numerals to the accompanying drawings which illustrate a practical embodiment of our invention, 10 designates the spout or nozzle of a charged water delivery faucet, the end of said faucet being externally threaded for the reception of a bushing 11. Detachably secured to bushing 11 by means of screws 12 is the upper portion of a vertically disposed tubular member 13, the lower portion of which is constructed to form a discharge nozzle 14, and secured in any suitable manner on the side of the tubular member is a housing 15 that con-

tains a small motor, and which latter consists of a spiral spring and a train of gearing. This spring motor forms no part of our invention as there are a number of spring motors readily obtainable in the open market that may be used in the operation 55 of our improved mixer.

The train of gearing in the motor is utilized for driving a shaft 16 that projects through the wall of tubular member 13 and said shaft carrying on its outer end a 60 beveled pinion 17.

A vertically disposed shaft 18 extends axially through the lower portion of tubular member 13, said shaft being journaled for rotation in bearings 19 and the upper end of 70 said shaft carrying a beveled pinion 20 that meshes with pinion 17. Shaft 18 projects a substantial distance below the lower end of nozzle 14 and secured to the lower end of said shaft is a mixing head 21.

75 The spring motor within housing 15 is normally held against operation by a detent 22, the point of which engages between the teeth of one of the gear wheels in the train. Arranged for sliding movement in suitable 80 bearings in housing 15, is a vertically disposed rod 23 with which cooperates a coil spring 24 that yieldingly resists forward movement of said rod and the lower end of this rod terminates in the same horizontal 85 plane with the lower end of nozzle 14.

Secured to the lower end of rod 23 and disposed to the side of the discharge end of nozzle 14, is a horizontally arranged arcuate plate 25 having on its outer edge a depend- 90

95 The spiral spring of the motor within housing 15 is wound up by means of a small crank handle 27 that is mounted on the main spring carrying shaft 28.

Rod 23 carries a shoulder or stud 29 that is adapted to engage the tail of detent 22 to force the point thereof into engagement with one of the gear wheels of the train of gearing in housing 15 and a comparatively light 100 spring 30 bears on the tail of said detent and acts to move the point thereof out of engagement with the gear wheel when the pin or shoulder 29 is elevated and moves away from the tail of the detent.

105 In the operation of our improved mixing device, a drinking glass containing syrup or flavoring extract is positioned beneath the

attachment so that the lower portion of shaft 18 and mixing head 21 are positioned within said glass and the latter is elevated until the upper edge of said glass contacts with plate 25. The application of a slight pressure to said plate will raise same and move rod 23 upward, thereby lifting pin or shoulder 29 from detent 22, thereby permitting spring 24, that is associated with said 10 detent, to shift same so that its point is disengaged from the teeth of the gear wheel and the train of gearing under the influence of spiral spring of the motor will act to drive shaft 16 and the motion of the latter is transmitted through pinions 17 and 20 to shaft 18 carrying the mixing head 21.

When the valve of faucet 10 is open, the charged water will discharge downwardly through member 13 into the glass and, as 20 the head 21 continues to rotate, the charged water will be thoroughly mixed with the syrup or flavoring extract while the charged water is flowing into the glass and consequently accomplishing the desired results.

As soon as the pressure of the drinking glass is relieved from plate 25, spring 24 will act to move rod 23 downward, thus moving detent 22 into engagement with the teeth of the gear wheel forming a part of the train 30 within housing 15 and consequently stopping further operation of the device.

Thus it will be seen that we have provided a mixing attachment for soda faucets that is relatively simple in construction, capable of being easily and cheaply produced and which is very effective in performing the functions for which it is intended.

It will be understood that minor changes in the size, form and construction of the various parts of our improved automatic mixer may be made and substituted for those herein shown and described without departing from the spirit of our invention, the scope of which is set forth in the appended 45 claims.

We claim as our invention:

1. A mixing attachment for soda dispensing faucets comprising a tubular member adapted to be detachably applied to the dis-

charge end of the faucet, a spring motor 50 driven member carried by and depending from said tubular member, a mixing head carried by said depending member and means adapted to be engaged by a container positioned beneath the attachment for throwing into operation the spring motor that actuates the mixing head carrying member.

2. The combination with a soda dispensing faucet, of a tubular member detachably connected to said faucet, a mixing member 60 mounted for rotation within said tubular member and depending therefrom, which mixing member includes a mixing head, means mounted on the side of the tubular member for actuating said mixing member and means adapted to be actuated by a container positioned beneath the tubular member for throwing into operation the mixing member actuating means.

3. A mixing attachment for soda dispensing faucets comprising a tubular member adapted to be detachably applied to a faucet, a shaft journaled in and depending from said tubular member, a mixing head carried by the lower end of said shaft, a motor 75 mounted on said tubular member, releasing means associated with said motor and means having a portion located adjacent to the discharge end of said tubular member for actuating said releasing means.

4. The combination with a soda dispensing faucet, of a tubular member detachably applied to said faucet, a shaft journaled in and depending from said tubular member, a mixing head carried by the lower end of 85 said shaft, a spring motor carried by said tubular member and connected to the mixing head carrying shaft for operating the same, releasing means associated with the motor and a plate forming a part of said releasing means, which plate is positioned adjacent to the discharge end of the tubular member so as to be engaged by a container positioned below the mixing device.

In testimony whereof we affix our signatures.

FRANK I. GUNNELL.
RALPH MILLER.
